UNITED STATES PATENT OFFICE.

JULIUS A. SCHWEIG, OF ST. LOUIS, MISSOURI.

GUIDE SHOE FOR ELEVATOR DOORS.

Application filed June 20, 1927. Serial No. 199,942.

This invention relates to guide shoes for vertically sliding fire-proof elevator doors. It has for its principal objects to devise a cheap and efficient guide shoe which can be quickly and easily secured in place and which can be readily adjusted to take up wear and obtain the desired play between the door and the door guides. Another object is to provide means for releasing the guide shoe in the event of fire and thus prevent binding of the door when the metal parts expand due to the heat of the fire. Other objects are simplicity of construction and compactness of design.

15 The invention consists principally in the improved guide shoe and in the combinations and arrangements of parts hereinafter described and claimed.

In the accompanying drawing, which 20 forms part of this specification and wherein like symbols refer to like parts wherever they occur.

Fig. 1 is a horizontal cross-section on line 1—1 of Figure 2 through the adjacent side 25 frame members of a vertically sliding fire-proof elevator door construction provided with a guide shoe embodying my invention.

Fig. 2 is an interior side elevation of the parts shown in Fig. 1, and

30 Fig. 3 is an edge view of the door showing a guide shoe secured thereto.

Referring to the accompanying drawing, my invention is shown in connection with a vertically sliding fire-proof elevator door 35 construction comprising a metal clad closure or door section A arranged for vertically sliding movement across the door opening B in an elevator shaft. As shown in the drawing, the metal clad door section A is provided along each vertical edge with an angle bar side frame member 4, whose outstanding flange is slidably arranged between the spaced parallel flanges of angle bar guides 5 and 6 that are rigidly secured to each other 40 and to the adjacent jamb member 7 of the door opening. This construction of fire-proof elevator door is well known and it is considered unnecessary to illustrate it in detail.

45 The door guide or shoe preferably comprises a base flange 8, which is rigidly secured flatwise to the outer face of the inner leg of the door angle 4 preferably by means of bolts 9, and two horizontally spaced vertically disposed outstanding guide flanges 10,

which straddle the free outstanding flange of the guide rail 5. Located between the spaced guide flanges 10 of the guide shoe for horizontal sliding movement towards and away from the edge of the flange of the guide angle straddled by said guide flanges is a metal bearing block 11. The bearing block is slidably supported between the guide flanges 10 preferably by means of a horizontal bolt 12 whose head portion is slidably supported in a horizontal slot 13 in one of said guide flanges and whose shank portion passes through a hole provided therefor in said bearing block and a horizontal slot 14 in the other of said flanges. The bearing block is adapted to be clamped in any desired position of its sliding movement by means of a nut 15 threaded on supporting bolt 12, which is also provided between said nut and the face of the adjacent guide flange of the 70 guide shoe with a metal washer 16, and a washer 17 made of fiber or other combustible substance.

The metal bearing block is moved in the direction of the guide angle to take up excessive side play of the door by means of a vertically slidable wedge 18 made of fiber or other combustible substance and mounted in a vertical slot 19 provided therefor in the base flange 8 of the guide shoe opposite the space between the spaced guide flanges thereof. The wedge extends between the spaced guide flanges of the guide shoe back of the bearing block; and the opposing side edges of said wedge and said block are bevelled off obliquely from top to bottom in a direction which will cause the slide block to be forced outwardly when the wedge is moved upwardly into engagement therewith. The wedge is forced upwardly into engagement with the bearing block preferably by means of an adjusting screw 20 which is threaded through an outstanding lug 8¹ formed integral with the base flange of the guide shoe immediately below the wedge. The upper end of the adjusting screw 20 bears against the lower edge of the wedge and thus serves to hold said wedge in the desired position of adjustment. As shown in the drawing, the adjusting screw is provided with a lock nut 21 for locking it in the desired adjusted position.

By the arrangement described, the metal bearing block 11 may be readily adjusted to take up wear and to secure the desired side 110

play between the door and the door guides by manipulating the screw 20 which moves the wedge 18. After such adjustment, the metal bearing block may be firmly clamped 5 in position by tightening the nut 15 on the bolt 12 which slidably supports said block; and the adjusting screw, which supports said wedge, may then be locked in the desired position of adjustment by means of the lock 10 nut 21. In the event of fire, the effect of the heat will cause the fiber washer 17 and the fiber wedge 18 to burn out or become disintegrated, thereby releasing the metal bearing block and thus preventing binding of the 15 door when then the metal parts of the door or door guides expand due to the heat of the fire.

It is noted that any desired number of 20 guide shoes may be secured to the side rail of the door, two shoes being ordinarily used on each side of the door.

The hereinbefore described arrangement admits of considerable modification, and I do not wish to be limited to the precise arrangements 25 shown and described.

What I claim is:

1. The combination with a frame member and a sliding closure member therefor, of a 30 guide for the sliding closure member, said guide being secured to one of said members in position to cooperate with the adjacent edge of the other of said members, a bearing block mounted on said guide between the opposing faces of said members, and means for 35 adjusting said block towards and away from said opposing faces to take up wear and to obtain the desired play therebetween.

2. The combination with a frame member and a sliding closure member therefor, of a 40 guide for the sliding closure member, said guide being secured to one of said members in position to cooperate with the adjacent edge of the other of said members, a bearing block mounted on said guide between the opposing faces of said members, means for 45 adjusting said block towards and away from said opposing faces to take up wear and to obtain the desired play therebetween, and means for securing said block in the desired 50 position of adjustment.

3. The combination with a frame member and a sliding closure member therefor, of a 55 guide for the sliding closure member, said guide being secured to one of said members in position to cooperate with the adjacent edge of the other of said members, a bearing block mounted on said guide between the 60 opposing faces of said members, means for adjusting said block towards and away from said opposing faces to take up wear and to obtain the desired play therebetween, means for securing said block in the desired 65 position of adjustment, and means whereby the securing means for said bearing block is adapted to be released by exposure to fire.

4. The combination with a frame member and a sliding closure member therefor, of a guide for the sliding closure member, said guide being secured to one of said members in position to cooperate with the adjacent 70 edge of the other of said members, a bearing block mounted on said guide between the opposing faces of said members, means for adjusting said block towards and away from said opposing faces to take up wear 75 and to obtain the desired play therebetween, means for securing said block in the desired position of adjustment, and means whereby the securing means for said bearing block is adapted to be released by exposure to fire, 80 said block adjusting means being combustible, whereby it is adapted to become disintegrated by exposure to fire.

5. The combination with a frame member and a sliding closure member therefor, of a 85 guide for the sliding closure member, said guide being secured to one of said members in position to cooperate with the adjacent edge of the other of said members, a bearing block mounted on said guide between the 90 opposing faces of said members, and means for adjusting said block towards and away from said opposing faces to take up wear and to obtain the desired play therebetween, said block adjusting means being combustible. 95 whereby it is adapted to become disintegrated by exposure to fire.

6. A guide shoe for vertically slidable fire doors comprising a bracket member adapted to be secured to the side edge of the 100 door and having spaced guide flanges adapted to straddle a guide rail for said door, a bearing block supported between said guide flanges for sliding movement towards and away from said guide rail, and a wedge for 105 forcing said block in the direction of said guide rail.

7. A guide shoe for vertically slidable fire doors comprising a bracket member adapted to be mounted between the side edge of the 110 door and a guide rail for said door, a bearing block mounted on said bracket member for sliding movement towards and away from said guide rail, and a wedge for forcing said block in the direction of said guide 115 rail.

8. A guide shoe for vertically slidable fire doors comprising a bracket member adapted to be secured to the side edge of the door and having spaced guide flanges adapted to straddle a guide rail for said door, a bearing block supported between said guide flanges for sliding movement towards and away from said guide rail, a wedge for forcing said block in the direction of said guide angle, 120 and means for locking said block in the desired adjusted position.

9. A guide shoe for vertically slidable fire doors comprising a bracket member adapted to be secured to the side edge of the door 125

and having spaced guide flanges adapted to straddle a guide rail for said door, a bearing block supported between said guide flanges for sliding movement towards and away from said guide rail, a wedge for forcing said block in the direction of said guide angle, and means for locking said wedge in the desired adjusted position.

10. A guide shoe for vertically slidable fire doors comprising a bracket member adapted to be secured to the side edge of the door and having spaced guide flanges adapted to straddle a guide rail for said door, and bearing block supported between said guide flanges for sliding movement towards and away from said guide rail, a wedge for forcing said block in the direction of said guide angle, means for locking said block in the desired adjusted position, and means where-
20 by the securing means for said bearing block is adapted to be released by exposure to fire.

11. A guide shoe for vertically slidable fire doors comprising a bracket member adapted to be secured to the side edge of the door and having spaced guide flanges adapted to straddle a guide rail for said door, and bearing block supported between said guide flanges for sliding movement towards and away from said guide rail, a wedge for forcing said block in the direction of said guide angle, means for locking said block in the

desired adjusted position, and means whereby the securing means for said bearing block is adapted to be released by exposure to fire, said wedge being combustible, whereby it is 35 adapted to become disintegrated when exposed to the action of fire.

12. A guide shoe for vertically slidable fire doors comprising a bracket member adapted to be secured to the side edge of the door and having spaced vertical guide flanges adapted to straddle a guide rail for said door, a bearing block disposed between said guide flanges with one edge in cooperative relation to said guide rail, a bolt extending through said bearing block and said flanges for clamping said block between said flanges, said flanges being provided with horizontal slots adapted to slidably support said bolt, a nut on said bolt, a combustible 50 washer between said nut and the flange adjacent thereto, a combustible wedge extending between said flanges in position to engage said bearing block to force the same in the direction of the guide rail, and an adjusting screw mounted on said guide shoe in position to move said wedge into engagement with said block.

Signed at St. Louis, Missouri, this 15th day of June, 1927.

JULIUS A. SCHWEIG.
